Application filed October 3, 1892. Serial No. 447,730. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification, reference being had to the accompanying drawing, forming part thereof.

10 The leading feature of this design consists of a series of festoons of flowers and leaves and a series of oval-shaped wreaths of flowers and leaves connected with the festoons and small fleur-de-lis ornaments arranged alternately 15 with the wreaths, as represented in the accompanying drawing. The wreaths of flowers and leaves are suspended by ribbons from

the center of each festoon, and the ends of the ribbons hang in wavy lines through the center of the wreaths. The festoons of flowers and leaves appear suspended from the wreaths above the festoons. 20

The design is printed in any desired color or colors upon tinted paper of any desired color. 25

What I claim—

The design for wall-paper herein shown and described.
